(57) **CLAIM**

The ornamental design for LED front side light with daytime running lights, as shown and described.

DESCRIPTION

FIG. 1 is a front isometric view of the LED front side light with daytime running lights design;

FIG. 2 is a back isometric view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

A pair of this LED front side light with daytime running lights design forms a bilateral symmetry structure. Each LED front side light with daytime running lights design has three units, including day time running light, parking lamp and turn signal light. The grille part of the design includes day time running light and turn signal light. The side part is parking lamp. The design is a full LED light source design, energy saving, beautiful and reliable, making driving safer.
